UNITED STATES PATENT OFFICE.

COSTANTINO P. RALLO, OF WASHINGTON, DISTRICT OF COLUMBIA.

STAND FOR WATER-COOLERS.

SPECIFICATION forming part of Letters Patent No. 398,446, dated February 26, 1889.

Application filed March 4, 1887. Serial No. 229,730. (No model.)

To all whom it may concern:

Be it known that I, COSTANTINO P. RALLO, a citizen of the United States, residing at Washington city, in the District of Columbia, have invented certain new and useful Improvements in Stands for Water-Coolers; and I do hereby declare the following to be a full, clear, and exact description of the invention, such as will enable others skilled in the art to which

it appertains to make and use the same.

My invention relates to improvements in stands for water-coolers; and the object of the invention is to produce a stand for water-coolers more especially adapted for halls in houses or public buildings; also, to provide said stand with an adjustable supporter for the glasses or tumblers; also, to form a receptacle for the drip-water, while at the same time said receptacle forms a receiver for umbrellas, &c., and, finally, to suspend the water-cooler on a light and ornamental stand, so that it can be easily removed for cleaning, filling, &c., while at the same time it always assumes its former position.

The invention consists in the construction of certain details and arrangement of parts, as will be more fully described hereinafter, and specifically pointed out in the claim, reference being had to the accompanying drawings and the letters of reference marked thereon.

Similar letters of reference indicate like parts in the different figures of the drawings, in which—

Figure 1 represents a front elevation of my improved water-cooler stand. Fig. 2 is a vertical cross-section, at right angles to Fig. 1, of the cooler and stand. Fig. 3 is a horizontal section on line *x x*.

In the drawings, *A* represents a frame or stand, which may be of any suitable material and size and can be made very ornamental, if desired. This frame is provided with hooks *a*, upon which the water-cooler *B* is suspended either by eyes *b* or straight pins or lugs, so as to be easily removable and yet that it always assumes its former position.

The water-cooler herein shown consists, preferably, of an outer shell, *C*, made of wood or metal or lined with some non-conducting material, and is closed by a cover, *D*. Within the

shell is arranged the water-receptacle *E* in such manner as to leave an annular space, *d*, in which the ice is to be placed for cooling the water. The inner receptacle is also provided with a cover, *F*, and it may be made removable or secured to the shell *C*. A suitable spigot, *c*, serves to withdraw any water from the inner receptacle when desired.

In the lower part of the frame is arranged a receptacle, *G*, of sufficient depth to serve as a receiver for umbrellas, while at the same time serving to contain the drip or waste water from the cooler. The receptacle may also be made of wood, metal, or lined with one or the other. It may also be made detachable or permanent, as desired. On the upper edge of the receptacle *G* is secured a stand, *H*, upon which an adjustable holder, *I*, for the tumblers or drinking-vessels is supported, so as to be adjustable vertically as well as horizontally to suit the position of the spigot in the cooler.

The holder *I* has an annular flange, *i*, and is provided with a short drip-pipe to which a rubber or flexible tube, *k*, is attached, to lead the waste or drip water into the receptacle *G*, and this may also be provided with a spigot, *g*, for withdrawing or emptying it of any accumulated water. The frame or stand may be made portable, or if of very large size it may be made permanent—for instance, for hotels, public buildings, schools, &c. The main part of the frame can also be made of solid iron or of tubes or pipes to lighten it. Stops may be provided to prevent swinging of the cooler.

The advantages of my improved water-cooler will be readily appreciated, and among them may be mentioned that the water will always have a pure taste, as it does not come in contact with the ice, while being sufficiently cold for health. An inferior or cheaper quality of ice can be used and not so much care is required in washing or cleaning the ice. There will be no liability of ruining carpets by waste water, &c. It forms a neat receptacle for umbrellas, &c., and it can be produced at a very small expense.

Having thus described my invention, what I claim, and desire to secure by Letters Patent, is—

The stand for water-coolers herein described,

consisting of the arched frame A, provided with hooks *b* on its uprights for suspending a water-cooler, in combination with the receptacle G, secured to said frame, and said receptacle provided with the stand H, upon which the glass-holder I, having flange *i*, can be adjusted, and the flexible tube *k*, all arranged as shown, and for the purpose set forth.

In testimony whereof I affix my signature in presence of two witnesses.

COSTANTINO P. RALLO.
